CUTOFF CYLINDER

Herman A. Doppelb, Hamilton, Ohio, assignor to
The Hamilton Tool Company, Hamilton, Ohio,
a corporation of Ohio

Application November 9, 1951, Serial No. 255,668

5 Claims. (Cl. 164—66)

1

This invention relates to blade cylinders and more particularly to a cut off blade cylinder for rotary presses, and the like.

An object of the invention is to provide a cut off blade cylinder with means for continuously and automatically directing a blast or current of air from the periphery of the cylinder rearwardly of the blade thereof, for precluding adherence onto the periphery of the cylinder of the forward or leading portion of the web of material being severed into shorter lengths by the cylinder.

Heretofore considerable difficulty has been experienced in those instances wherein rotary cut off means have been utilized for severing continuous lengths of sheet material, such as paper, into shorter lengths or sheets, and particularly when the rotational speed of the cut off cylinder has been relatively high. When paper, in particular, is severed under such conditions, there is a pronounced tendency for the forward edge of the sheet next to be severed from the continuous web to adhere to the outer periphery of the cylinder, rearwardly of the cutting blade, thereby elevating or lifting said forward edge. This lifting of the forward edge of the sheet next to be severed precludes its proper discharge upon, and registry with the last severed sheet, and often results in a bunching up of severed sheets adjacent the cut off cylinder.

A further object of the invention is to provide means for effectively eliminating the tendency of the forward edge of the sheet next to be severed from a continuous roll to lift or tend to adhere to the outer periphery of the blade cylinder.

Still a further object of the invention is to provide simple, inexpensive, yet highly efficient means for positively deflecting the forward portions of the sheet next to be severed from a continuous web downwardly toward and onto the previously severed sheet, thereby facilitating high speed operations of the cut off blade cylinder with precise registry of the severed sheets.

These and other objects are attained by the means described herein and as disclosed in the accompanying drawings, in which

Fig. 1 is a side elevational view of a cut off blade cylinder embodying the teachings of the present invention.

Fig. 2 is an enlarged cross sectional view on line 2—2 of Fig. 1, the cut off blade cylinder being shown in the association with other portions of a typical cut off machine assembly and with the cut off blade in position at the moment of cut off.

Fig. 3 is a view similar to Fig. 2 showing the relationship of the cut off cylinder after cut off.

2

Fig. 4 is a sectional view of a cut off cylinder illustrating a modified form of the invention.

Fig. 5 is a view similar to Fig. 4 illustrating still another modification of the invention.

5 With particular reference now to Fig. 1, the numeral 10 denotes generally a cut off cylinder such as used in the printing industry, said cylinder including a transversely extending blade 12 having a cutting edge 14 projecting outwardly beyond the outer periphery 16 of the cylinder.

As best illustrated in Fig. 2, the cutting edge 14 of blade 12 is adapted to make kissing contact with the cutting edge of a fixed blade 18 for thereby severing a continuous web 20 into a plurality of individual sheets 22, which sheets will be deposited in echelon relationship upon a suitable support 24 thence onto the upper reach 26 of an endless conveyor denoted generally by the numeral 28.

15 The present invention is neither directed to nor concerned with the specific structural details of the cylinder or its blade, these devices being old and well known to the art.

20 The present invention is directed to the provision of simple, highly effective means for inducing a steady flow or current of air for positively deflecting the free outer, or leading edge 40 of the next sheet to be severed from web 20 downwardly, that is, away from cylinder 10 and toward the upper face of the preceding sheet severed by blade 12 on the preceding revolution of the cylinder.

25 Such means may comprise a plurality of laterally spaced conduits or passageways 42 each having an inlet end 44 in the periphery of the cylinder immediately forwardly of blade 12, and an outlet port 46 in the cylinder periphery adjacent the rear end 62 of blade 12. Such a conduit or passageway may be provided in the body of cylinder 10 by a milling or any other conventional operation.

30 Suitable means are provided immediately in advance of the outer or forward end 50 of blade 12 for scooping air into conduit 42 incident to rotation of cylinder 10.

35 As illustrated in Figs. 2, 3 and 5, such means may comprise an elongate panel 52 mounted between adjacent portions of cylinder 10 and rear face 54 of the blade, wherein the term rear face of the blade refers to that face remote from and parallel with front or forward face 56. Panel 52 includes a portion 58 which extends outwardly beyond the outer periphery 16 of cylinder 10 by an amount less than the amount by which cutting edge 14 of the blade projects from periphery 16.

40 If desired, panel 52 may be securely though releasably anchored by means of a plurality of bolts

60 which extend through suitable apertures in blade 12 for engaging tapped holes provided in cylinder 10. It will be noted that the same means are thus utilized for anchoring panel 52 as are utilized to mount blade 12 relative to the cylinder.

In the preferred embodiment of the invention discharge ports 46 are disposed immediately adjacent inner or rear end 62 of blade 12 for thereby discharging the air scooped into conduit 42 as close to blade 12 as possible.

With reference now to Fig. 3, it will be observed that a current of air denoted generally by the headed arrows 70 will enter conduit 42 at inlet 44, and be discharged via outlet 46, thereby positively deflecting the leading end 40 of the next sheet to be severed from web 20 downwardly toward the upper surface of the previously severed sheet 22.

With reference now to Fig. 4, it will be noted that the scooping means may, if desired, comprise a substantially L-shaped member 78, one leg 80 of which is secured to and carried by the outer or forward end 50 of blade 12 such as by means of set screws 82 or the like, for thereby disposing its other leg 84 along and as a continuation of the rear face 54 of the blade, which rear face may be described as that side of the blade remote from cutting edge 14. The air-scooping characteristics of leg 84 are similar to those of portion 58 of panel 52.

It will be noted that adjustment of blade 12 relative to cylinder 10 may be at all times accomplished by means of bolts 60.

The modified form of the invention illustrated in Fig. 5 is the same in construction as the construction shown in Figs. 1, 2 and 3, except that it includes means in the form of a bolt 85 for effecting endwise adjustment of the blade 12 relative to the cylinder.

From the foregoing, it will be noted that I have thus provided simple, yet highly effective, fully automatic, non-mechanical means for inducing a current of air, incident to rotation of the blade cylinder, to deflect the leading edge of the next sheet to be severed from a continuous web 20.

In the preferred embodiment of the invention I provide a plurality of laterally spaced conduits 42, one between each blade holding bolt 60, it being noted that each conduit extends along the rear face 54 and rear ends 62 of the blade.

Uniformly satisfactory results have been obtained when each of the conduits is of substantially uniform width throughout its entire length. The depth of each conduit preferably varies uniformly from a maximum depth at its inlet or intake end 44 to a minimum depth at the rear end of the blade. Solely by way of example, and in order to enable others to practice my invention without having to resort to experimentation, I have found that excellent results are obtained when the width of the conduits approximates one-half inch and when the depth varies from three-eighths of one inch at the inlet end to one-eighth inch along the rear face of the blade at its rear edge.

It should be understood that various changes and modifications may be made in the structural details of the device, within the scope of the appended claims, without departing from the spirit of the invention.

What is claimed is:

1. In combination with a cut off blade cylin-

der of the type which includes a transversely extending blade having a cutting edge projecting outwardly beyond the outer periphery of the cylinder, of means on the cylinder disposed in advance of said cutting edge and projecting outwardly beyond the outer periphery of the cylinder for scooping air incident to rotation of the cylinder, and means interconnecting portions of the cylinder immediately in advance of said first mentioned means with portions of the cylinder periphery at the end of the blade opposite its cutting edge for discharging air scooped by said first mentioned means rearwardly of said blade.

2. In combination with a cut off blade cylinder of the type which includes a transversely extending blade having a cutting edge projecting outwardly beyond the outer periphery of the cylinder, of means on the cylinder disposed in advance of said cutting edge and projecting outwardly beyond the outer periphery of the cylinder for scooping air incident to rotation of the cylinder, said cylinder provided with a plurality of laterally spaced conduits leading from and interconnecting portions of the cylinder immediately in advance of said means with portions of the cylinder periphery at the end of the blade opposite its cutting edge and arranged to have flow of air induced therethrough incident to rotation of the cylinder.

3. A cut off blade cylinder as defined in and by claim 2, wherein said air scooping means comprises an elongate panel mounted between adjacent portions of the cylinder and blade.

4. A cut off blade cylinder as defined in and by claim 2, wherein said air scooping means comprises a substantially L-shaped member one leg of which is secured to and carried by the blade for locating the other leg along and as a continuation of that side of the blade remote from its cutting edge.

5. In combination with a cut off blade cylinder of the type which includes a transversely extending blade having a cutting edge projecting outwardly beyond the outer periphery of the cylinder, of means on the cylinder disposed in advance of said cutting edge and projecting outwardly beyond the outer periphery of the cylinder for scooping air incident to rotation of the cylinder, said cylinder provided with a plurality of laterally spaced conduits leading from and interconnecting portions of the cylinder immediately in advance of said means with portions of the cylinder periphery at the end of the blade opposite its cutting edge and arranged to have flow of air induced therethrough incident to rotation of the cylinder, wherein the width of each conduit is substantially uniform and wherein the depth uniformly varies from a maximum depth adjacent the inlet end to a minimum depth at the rear end of the blade.
